UNITED STATES PATENT OFFICE.

PEARL LE DOUX, OF OAKLAND, CALIFORNIA.

DESIGN FOR A COMBINATION DOLL AND PIN CUSHION.

Application filed November 20, 1922. Serial No. 4,348. Term of patent 3½ years.

To all whom it may concern:

Be it known that I, PEARL LE DOUX, a citizen of the United States, residing at Oakland, in the county of Alameda, State of California, have invented a new, original, and ornamental Design for Combination Doll and Pin Cushion, of which the following is a specification, reference being had to the accompanying drawing, forming part thereof.

In the drawings:

I claim:

The ornamental design for a combination doll and pin cushion substantially as shown.

In testimony whereof, I have hereunto set my hand this 6th day of November, 1922, in the presence of the two subscribed witnesses.

MRS. PEARL LE DOUX.

Witnesses:

E. M. Ross,
Iva GOODENOUGH.
